UNITED STATES PATENT OFFICE.

SETH A. CRONE, OF EAST ORANGE, NEW JERSEY, ASSIGNOR TO BUFFALO BRAKE BEAM COMPANY, OF NEW YORK, N. Y., A CORPORATION OF NEW YORK.

RAILWAY BRAKE BEAM.

Application filed February 12, 1925. Serial No. 8,620.

To all whom it may concern:

Be it known that I, SETH A. CRONE, a citizen of the United States, and a resident of East Orange, in the county of Essex and 5 State of New Jersey, have invented certain new and useful Improvements in Railway Brake Beams, of which the following is a specification.

The invention pertains to trussed brake-beams for railway-cars and especially to a 10 novel strut interposed between the compression and tension members of the beam.

One purpose of the invention is to provide a 15 novel forged metal strut having suitably spaced-apart sides to receive between them the usual brake-lever, means at the back end of the strut for engagement with the compression member of the beam and special means at the forward end of the strut to 20 afford an adequate seat for and effectually retain the forward curved central portion of the tension member or truss-rod.

One difficulty incident to the production 25 of one-piece forged metal struts, has resided in discovering a method of providing an adequate seat for the truss rod,—a seat which will securely retain the rod in place during the practical use of the beams and a seat which in itself is of sufficient strength 30 to withstand modern railway requirements.

My invention has more particular reference to the forward or seat-end of the strut, and in accordance with my method of manufacture I reinforce the seat-end of the strut 35 with the use of a U-shaped bar or insert applied thereto with the legs of the bar or insert projecting forwardly, said legs being positioned to extend above and below and receive between them the truss rod, and said 40 legs being of adequate length to effectually retain the truss rod on the strut-end and of suitable width to present broad smooth surfaces to said rod.

The strut comprises a main forged metal 45 bar folded into U-form and the auxiliary forged metal U-bar or insert which I apply to the seat end of the strut for reinforcing said end and providing adequate means to receive and retain the truss rod.

50 The invention will be fully understood from the detailed description hereinafter presented, reference being had to the accompanying drawings, in which:

Fig. 1 is a side elevation of a brake-beam strut shown in position in a brake-beam, the

compression and tension members of the beam being indicated in vertical transverse section:

Fig. 2 is a top view of the forward end portion of the same, a part of the tension member or truss rod being indicated by dotted lines;

Fig. 3 is a front end view of the same, with a portion of the tension member shown by dotted lines;

Fig. 4 is a longitudinal section through a portion of the same, the section being on the dotted line 4—4 of Fig. 3;

Fig. 5 is a perspective view showing the middle portion of the flat bar from which 70 the body of the strut is formed and the U-shaped forged metal insert I apply to the slits in said portion of the bar in providing a seat and retainers for the truss rod or tension member of the beam;

Fig. 6 is a horizontal section, partly broken away, of a modified construction of 75 brake-beam embodying my invention, the section being on the dotted line 6—6 of Fig. 7, the beam shown in Fig. 6 being 80 of known type employing a vertically disposed brake-lever as distinguished from one set at an angle of forty degrees from the vertical and requiring the type of strut shown in Fig. 1;

Fig. 7 is a vertical section through the same, taken on the dotted line 7—7 of Fig. 6.

Figs 8 and 9 are perspective views showing, respectively, the middle portion of 90 the initially flat bar from which the strut shown in Figs. 6 and 7 is formed and a U-shaped metal insert I apply to the slots formed in said bar in providing a seat for the truss rod of the beam;

Fig. 10 is a vertical section through the bar shown in Fig. 8 and illustrates the U-shaped inserts as having been applied to the slots therein, Fig. 10 showing the parts in their initial shape and relation to each 100 other, and

Fig. 11 is a perspective view, partly in section and partly broken away, showing a further and less desirable way of applying the U-shaped insert to the bar.

Referring to Figs. 1 to 5 inclusive, 10 designates the strut as a whole, 11 the compression member and 12 the tension member comprising a trussed brake-beam for railway-cars.

The main body of the strut 10 is formed from a single bar of forged metal folded at its middle portion into approximately U-shape having parallel sides 13, 14, and members, as 15, for illustration, at the free ends of said sides to engage the compression member, which may be of any suitable cross-section. By suitably twisting the sides 13, 14 at their rear portions, as at 16, in a well-understood manner, the main body of the sides is caused to lie at an angle of forty degrees from the vertical, as shown in Figs. 1 and 2, to suitably receive between them the brake-lever, not shown, as usual.

15 My invention resides in a special formation of the forward end of the strut to adapt the same to adequately receive and retain the middle portion of the truss-rod.

In carrying out my invention, in the form 20 shown in Figs. 1 to 5 inclusive, I form two slits 17, 18 (Fig. 5) lengthwise of the flat bar from which the body of the strut is to be formed, these slits being parallel with each other and positioned to extend transversely 25 across that portion of the bar constituting, when the bar is U-ed, the fold or bend 19 which finally receives the truss-rod. The slits 17, 18 are formed in the bar while the metal is hot and by means of a tool which leaves the inner or adjacent sides 20, 21 of the slits smooth and straight and which displaces or swells the metal at the outer sides of said slits outwardly, as at 22, 23. In forming the slits 17, 18 no portion 30 of the metal is cut away and the metal of the bar is slit lengthwise of the grain thereof, no portion of the metal being cut across the grain thereof.

After the slits 17, 18 have been formed in 40 the flat bar, I apply to the bar at what is to be the inner side of the fold or bend 19, a forged metal bar or insert 23 which is of approximately U-shape and comprises a back member 24 and forwardly projecting legs or 45 arms 25. The insert 23 when applied to the main bar is hot and the legs or arms 25 of the insert are driven through the slits 17, 18 until the back member 24 of the insert engages the adjacent face of the main bar.

50 After the insert 23 has been applied to the main bar, said bar is subjected to the folding or bending operation and its folded or bent end is, on this operation, acted on by male and female dies to transform that end into an outline adapting the same to receive and retain the truss-rod, as shown in Figs. 1, 2, 3 and 4. One effect of the dies, on this final operation, is to twist the forwardly projecting portions of the arms 25 diagonally in opposite directions on concave lines (Fig. 3), whereby broad curved smooth parallel surfaces 26 are presented for seating and retaining the truss-rod, one of said arms 25 with its seating and retaining surface 26 being extending forwardly at the upper side of

said rod, and the other arm 25 with its seating and retaining surface 26 being extended forwardly at the lower side of said rod and both of said arms being of such length that they efficiently act as keepers for said 70 rod. Another effect of the final action of the dies is to concave the seat portion 19 between the arms 25, as at 27 (Fig. 4) to harmonize and cooperate with the concave surfaces 26 of the arms 25. Another effect of the final action of the dies is to crowd the outwardly displaced portions 22, 23 of the main bar, inwardly against the base portions 75 of the arms 25, as denoted at 28 (Fig. 4).

It will be apparent that the forward end of the strut constructed in accordance with my method of procedure is one of great strength and resisting power and capable of efficiently performing all of the duties required by modern railway service. It will be apparent also that under no circumstances could the retaining arms 25, after the strut has been completed, escape from the main bar, this being due in part to the reverse twisting of said arms, as shown in Fig. 3, to occupy the diagonally opposite positions shown and engage the truss rod. The insert 23, when in its final position shown in Figs. 1, 2, 3 and 4, becomes a fixed part of the strut and presents features of efficiency not heretofore attained, so far as I know in forged metal struts.

In the construction shown in Figs. 6, 7, 8, 9 and 10, 29 denotes the strut, 30 the compression member of the beam and 31 the 100 truss rod or tension member. The construction shown in Figs. 6 to 10 inclusive is intended for the class of trucks calling for vertically disposed brake levers, instead of 105 brake levers standing at an angle of 40° to the vertical, as would be the case of the strut shown in Fig. 1. A great many cars of foreign make require the construction of strut adapted to receive between its sides a vertically disposed brake lever. The flat bar from which the body of the strut 29 is formed will, while in the flat, have openings 32, 33 formed in it, these openings being 110 parallel with and opposite to each other and extending lengthwise of the bar. The openings 32, 33 are located in that part of the bar which, when the bar is folded to form the strut, will extend transversely across the bend or fold of the bar and which I number 34. I apply to the openings 32, 33 an insert 35 which is substantially the same as the insert 23 shown in Fig. 5. The insert 35 115 comprises a back member 36 and parallel arms or legs 37 which project forwardly and which I insert through the openings 32, 33 in the flat bar. The insert 35 is substantially of U-shape and will be applied to the main bar while said bar is in a heated condition and while said insert is hot. After 120 the insert 35 has been applied to the flat 125

forged bar, said bar is U-ed or folded and at the same time subjected to the action of dies which will concave the bend or fold 34 of the strut to form a transverse concave seat for the truss-rod and at the same time crowd the leg members 37 of the insert 35 in a direction outwardly from each other, as shown in Fig. 3, to receive between them the rod 31. The inner facing surfaces of the 10 leg members 37, 37, by the action of the dies, are concaved to match the concavity formed in the end of the bend or fold 34 so as to form a continuous sea extending against a large surface of the truss rod 31. The metal 15 at the outer sides of the openings 32, 33 becomes crowded against the outwardly flaring portions of the leg members 37, as shown in Fig. 7, so that a very rigid connection of the insert 35 with the forward end of the 20 strut results, it being impossible for the insert 35 to escape from the bend or fold of the strut.

In Fig. 11 I illustrate a further modified construction of a portion of the invention, 25 this modification residing in providing longitudinal recesses 38 in the opposite edges of the flat bar to receive the legs 39 of the insert member 40 in lieu of forming the openings 32, 33 in the bar and in lieu of forming 30 the openings 17, 18 in the manner shown in Fig. 5.

I prefer the construction shown in Fig. 1 for modern railway equipment, and the construction shown in Fig. 6 is necessary when 35 the strut is compelled to accommodate vertically disposed brake levers.

In accordance with my invention I do not weaken the sides of the strut in any respect, but do materially strengthen the forward 40 end of the strut and at the same time provide adequate means for effectually retaining a truss rod against its seat at the end of the strut.

What I claim as my invention and desire 45 to secure by Letters Patent, is:

1. A brake-beam strut comprising a folded forged metal bar having sides to receive between them a brake-lever, means at the free ends of said sides for engagement with a 50 compression member, a fold or bend at its forward end to receive a tension member and a forged metal insert applied to said fold and having forwardly projecting arms to extend above and below and retain the 55 tension member.

2. A brake-beam strut as claimed in claim 1, in which said insert is approximately of U-shape and has its back member against the inner face of said fold and its arms projected forwardly beyond said fold.

3. A brake-beam strut as claimed in claim 1, in which the forward face of said fold is concaved to form a seat for the tension member, and in which said insert is approximately of U-shape and has its back member

against the inner face of said fold and its arms projected forwardly beyond said fold and concaved outwardly at their inner end portions in continuation of said concave seat.

4. A brake-beam strut as claimed in claim 1, in which said insert is a bar bent into U-shape and of considerably greater width than thickness so as to present broad smooth surfaces to the tension member.

5. A brake-beam strut as claimed in claim 1, in which said bar at its middle or fold portion is cut to receive said arms and permit them to project forwardly with due regard to the upper and lower sides of the 80 tension member.

6. A brake-beam strut as claimed in claim 1, in which said insert is a bar of considerable width bent into approximately U-shape and has its back member against the inner face of said fold and its arms projected forwardly beyond said fold, and in which the main bar at its fold portion is cut to receive and permit the forward 85 projection of said arms.

7. A brake-beam strut comprising a forged metal bar folded at its middle portion to form sides to receive between them a brake lever and a fold at the forward end of the strut to receive a tension member, 90 and a forged metal insert applied at said fold and having forwardly projecting arms to extend above and below and retain the tension member, said bar being cut transversely at its fold portion to receive said arms, said sides being set at an angle of approximately forty degrees from the vertical and said arms at the outer side of said fold being diagonally reversely twisted to present smooth surfaces to the tension 95 member.

8. A brake-beam strut as claimed in claim 7, in which the forward face of said fold is concaved diagonally between said arms to form a seat for the tension member and in 110 which said arms adjacent to said fold are concave outwardly in their twisted portion to cooperate with said seat.

9. A brake-beam strut as claimed in claim 7, in which said insert is approximately of 115 U-shape and has its back member against the inner face of said fold and its arms projected forwardly beyond said fold.

10. A brake-beam strut as claimed in claim 7, in which said insert is a bar bent into approximately U-shape and of considerably greater width than thickness so as to present broad smooth surfaces to the tension member.

11. A brake-beam strut as claimed in claim 7, in which said bar at its fold portion has parallel openings cut inwardly from its side edges to receive said arms, said arms being secured by the metal of the bar at opposite 125 sides of said openings.

12. A brake-beam strut as claimed in claim 7, in which said insert is a bar of considerable width bent into approximately U-shape and has its back member against the inner face of said fold and its arms projected forwardly beyond said fold, and in which the main bar is cut inwardly from its side edges to form parallel longitudinal openings in its middle or fold portion to receive the arms of said insert, said arms being secured by the metal of the bar at opposite sides of said openings.

13. A brake-beam strut as claimed in claim 7, in which said insert is a bar of considerable width bent into approximately U-shape and has its back member against the inner face of said fold and its arms projected forwardly beyond said fold, and in which

the main bar is cut inwardly from its side edges to form parallel longitudinal slits, 20 pressed outwardly at their outer sides, in its middle or fold portion to receive the arms of said insert, said arms being secured by the metal of the bar at opposite sides of said slits.

14. A brake-beam strut as claimed in claim 1, in which said bar at its middle or fold portion has openings cut therein inwardly from its side edges to receive said arms and permit them to project forwardly, said arms 30 being held by the metal of the bar at opposite sides of said openings.

Signed at New York city, in the county of New York, and State of New York, this 10th day of February, A. D. 1925.

SETH A. CRONE.
